UNITED STATES PATENT OFFICE.

JOSHUA C. REYNOLDS, OF OWENSBORO, KENTUCKY.

APPARATUS FOR CURING TOBACCO.

1,413,783.

Specification of Letters Patent. Patented Apr. 25, 1922.

Application filed June 13, 1921. Serial No. 477,120.

To all whom it may concern:

Be it known that I, JOSHUA C. REYNOLDS, a citizen of the United States, residing at Owensboro, in the county of Daviess and 5 State of Kentucky, have invented certain new and useful Improvements in Apparatus for Curing Tobacco, of which the following is a specification.

This invention relates to means for curing tobacco and has for its primary object 10 the provision of an apparatus which may be readily moved from point to point as circumstances may require and by the use of which the exposure of the tobacco to flame 15 will be prevented and the curing of the tobacco accomplished easily with more uniform results than have been heretofore attained.

In many localities the method employed to 20 cure tobacco consists in kindling a fire in an open pit within an enclosure, upon the ceiling of which the tobacco has been hung. This method is obviously undesirable as frequently the fire acts directly upon the tobacco and consumes the same and also causes 25 damage to the barn or other enclosure. Moreover, the tobacco is frequently smoked and depreciated in value by this method. In other places, complicated and expensive 30 machinery has been employed, and it is the object of my invention to provide an apparatus which will eliminate all the objections of the open pit method and will be less expensive to install than the machinery which 35 has heretofore been employed.

One embodiment of my invention is illustrated in the accompanying drawings, in which—

Figure 1 is a side elevation of my im- 40 proved apparatus with a part in section;

Fig. 2 is a rear end elevation of the apparatus;

Fig. 3 is a front end elevation with the draft tongue removed;

Fig. 4 is a plan view partly broken away;

Fig. 5 is a plan view of the truck.

In carrying out my invention, I employ a truck consisting of front and rear bolsters 1 and 2 which may conveniently be wooden 50 blocks of proper dimensions. These blocks are secured upon standards or frame members which are formed at their upper ends with channels or side flanges 3 to receive the lower edges of the blocks, as will be readily understood upon reference to the drawings. The front frame member is shown as con-

sisting of a web 4 depending from the block-receiving channel and having its edges converging downwardly, as clearly shown in Fig. 3. At the lower end of this web 4, a disc 5 is formed and the said disc has a forwardly projecting perforated lug or ear 6 on its edge, an eye 7 being formed on the front side of the web to register with the lug 6, as will be readily understood upon 60 reference to Fig. 1. A sleeve 8 is fitted around the front axle 9 at the center of the same and the said sleeve is formed on its upper side with a disc 10 bearing against the under side of the disc or plate 5 and provided with 65 a perforated lug or ear 11 adapted to align axially with the lug or ear 7. The king bolt 12 is inserted through the lugs 7 and 11 and is retained therein by a washer and nut on its lower end, as indicated at 13. The members 5 and 10 constitute a fifth wheel to permit angular disposition of the front axle and, therefore, facilitate steering of the truck. The front wheels 14 are mounted 70 upon the ends of the axle 9 and are retained 75 thereon by nuts 15 in an obvious manner. At the inner sides of the wheels, sleeves or collars 16 are secured by pins or rivets to the axle and these collars or sleeves are provided at their front sides with forwardly projecting ears 17 between which are pivoted the rear extremities of the hounds 18. The hounds 18 are curved forwardly and inwardly and have their front extremities secured to the rear end of the draft tongue 80 or pole 19 which is equipped at its forward extremity with a handle 20 of any preferred construction. The channel receiving the rear bolster 2 is formed on the upper end of an arch-like web 21 which has its ends formed 85 into sleeves 22 through which passes the rear axle 23, the axle being fixed in the sleeve by rivets or pins, as will be readily understood. The extremities of the axle are tapered, as shown at 24, and skeins or bearing sleeves 90 25 are fitted upon the tapered portion of the axle against a stop collar 26 and retained on the axle by a nut 27. The skein or bearing sleeve has the ground wheel 28 rotatably fitted thereon and at the outer end of the skein 100 is an annular flange 29 which prevents the wheel from moving over the end of the skein. The front and rear bolsters are rigidly connected by bracing members 30 which are rigidly secured at their opposite ends to the 105 respective bolsters and converge from their ends toward their centers where they are 110 rigidly secured.

idly joined by rivets or similar devices 31. A very strong and inexpensive truck is thus produced which may be readily moved from point to point so that the apparatus mounted upon the truck may be used wherever desired.

The apparatus comprises a tank or reservoir 32 which will preferably be of seamless construction as it is to contain kerosene or other hydrocarbon and should be airtight so as to prevent excessive evaporation or leakage and to prevent the entrance of air except such as may be forced thereinto in the use of the apparatus, as will presently appear. This tank or reservoir is preferably of the elongated form illustrated in the drawings and it is secured upon the truck by bands 33 passed around the tank near the ends thereof and brought close together beneath the tank, as shown in Figs. 2 and 3 at 34, the ends of the bands being then carried sharply outwardly to rest upon and be secured to the bolsters, as shown at 35. A fastening bolt 36 is inserted through the adjacent portions of the band, and it will be readily noted that the spaced arrangement of the portions of the bands through which the bolts pass permits the bands to be drawn very tightly around the tank so that it will be firmly secured to the truck. The blocks constituting the body of the truck are firmly secured to the supporting channel members by bolts inserted vertically through all the members and these bolts are also utilized to secure the ends of the straps or bands to the bolsters. Lag screws may be also employed to further secure the ends of the bands to the bolsters, and bolts inserted transversely through the bolsters secure the ends of the braces 30 thereto. The tank 32 is provided at one end with a filling spout 37 and at any convenient point on its upper side is equipped with a pressure gage 38. An air admission valve 39 is also provided upon the tank and this valve may be of any well-known make. The inflation valve employed upon pneumatic tires will answer every purpose and as the particular construction of this valve does not form a part of my present invention, I have illustrated the same in a conventional manner only. In the use of the device, air is forced into the tank so as to be compressed to any desired degree, the reaching of which will be determined by the reading of the pressure gage and the pressure of the air upon the hydrocarbon liquid within the tank will force the same to the burner above the tank and also aid in vaporizing the fuel. The burner consists of a spraying nozzle 40 fitted in the lower end of a coil 41 and provided with a flattened extremity 42 whereby it may be readily engaged with a wrench or other turning tool when being fitted in the end of the coil. The coil is disposed vertically

and is fed by a pipe 43 which is connected with an outlet pipe 44 by a T-coupling 45. A plug 46 is removably fitted in the outer end of the T-coupling so that access may be readily had to the same and to the pipe 43 when cleaning thereof may be desirable. The outlet pipe 44 leads upwardly from the tank 32 and a cut-off valve 47, which is preferably a needle valve, is interposed in the said pipe between the tank and the feed pipe 43. An initial ignition pan 48 is mounted on the top of the tank immediately below the burner and is adapted to contain a small supply of the fuel which may be ignited to effect preliminary heating of the coil before igniting the fuel at the burner. When this initial supply of fuel has been consumed, the coil will be heated so that the fuel flowing therethrough to the burner will be rapidly and thoroughly vaporized and proper combustion will occur at the burner.

The coil and burner are disposed within a downwardly tapered drum or casing 49, the pipe 43 extending through the front end of said casing, as clearly shown. The top and bottom of this casing or drum are open so that air may readily flow to the burner and the heated air readily escape through the top of the casing or drum. The casing or drum is supported over the tank by standards or posts 50 at its ends and at its sides, the end standards or posts having their lower ends fitted in sockets 51 on the tank and their upper ends fitted in sockets 52 on the ends of the drum or casing, while the side posts or standards have their ends inserted through sockets 53 and 54 on the sides of the tank and the drum respectively and equipped with lock nuts 54 whereby they may be readily placed under the proper tension and the drum or casing firmly supported. Disposed over the drum and supported therefrom in spaced relation thereto by brackets 55 is a hood or cover 56 which is imperforate and effectually prevents flame from the burner rising through the top of the apparatus to act directly upon the tobacco to the detriment thereof. The open space between the opposed edges of the hood and the drum will, however, permit free circulation of air and escape of the heated air from the drum to circulate around and about the tobacco.

From the foregoing description, taken in connection with the accompanying drawings, it will be seen that I have provided a very simple portable apparatus whereby a high degree of heat may be readily generated and permitted to circulate through the tobacco to be cured so that the tobacco will be readily and quickly brought into the proper marketable condition. The apparatus may, of course, be made in various sizes and slight experience will enable the

user to determine how long the flame at the burner will be maintained, by a reading of the pressure gage inasmuch as the pressure originally established in the tank will be 5 that necessary to feed the fuel to the burner for a predetermined period at a given rate and as the pressure falls, the indications upon the pressure gage will by a process of elimination, show how much fuel is left in 10 the tank and how long it will supply the burner.

Having thus described the invention, what is claimed as new is:

1. An apparatus for the purpose set forth 15 comprising a portable tank, sockets on the sides of the tank, sockets on top of the tank near the ends of the same, a downwardly tapered drum arranged above the tank in spaced relation thereto and having open upper and lower ends, sockets on the sides and ends of the drum, posts having their lower ends secured in the sockets on the sides and top of the tank and their upper ends secured in sockets on the sides and ends of 20 25 the drum respectively, a burner in the open

lower end of the drum, and a fuel pipe leading from the tank to the burner.

2. An apparatus for the purposes set forth comprising a portable tank, a downwardly tapered drum supported by and above the 30 tank in spaced relation thereto and having open upper and lower ends, a burner in the open lower end of the drum, a fuel pipe leading from the tank to the burner, brackets rising from the upper edge of the 35 drum, and an arched hood carried by said brackets with its lower edge spaced above the upper edge of the drum.

3. An apparatus for the purpose set forth comprising a portable tank, a downwardly 40 tapered drum supported by and above the tank in spaced relation thereto and having open upper and lower ends, a burner in the open lower end of the drum, a fuel pipe leading from the tank to the burner, 45 and an arched hood carried by the upper end of the drum with an outlet at the juncture of the drum and the hood.

In testimony whereof I affix my signature.
JOSHUA C. REYNOLDS. [L. s.]
